[57] CLAIM

The ornamental design for a case for the holding and dispensing of cards, as shown and described.

DESCRIPTION

FIG. 1 is a front, side and top perspective view of a case for the holding and dispensing of cards, showing our new design in closed condition;

FIG. 2 is a top plan view thereof, the bottom being a mirror image;

FIG. 3 is a front elevation view thereof, the rear elevation being a mirror image;

FIG. 4 is a left side elevation view thereof;

FIG. 5 is a right side elevation view thereof;

FIG. 6 is a bottom plan view of our new design shown in open condition;

FIG. 7 is a top plan view thereof;

FIG. 8 is a front elevation view thereof, the rear being a mirror image;

FIG. 9 is a right side elevation view thereof; and,

FIG. 10 is a left side elevation view thereof.
